Application May 22, 1936, Serial No. 81,276

7 Claims. (Cl. 194—1)

This invention relates to a game apparatus of the type in which a successful player is rewarded by a certain number of free games. Thus, the invention may be applied to a game of the pin-ball type in which the player inserts a coin or token in order to release the balls with which the game is played. The player then plays the balls in succession in order to attain some objective, depending upon the detailed construction of the game. When this objective is attained, the player is rewarded by a number of free games which depends upon the rating and difficulty of the objective.

While the invention is disclosed herein in connection with a specific type of pin game, it must be understood that it is not intended to be limited thereto since the free game control apparatus herein described and claimed may be applied to all kinds of games of skill.

According to the present invention I prefer to provide the game apparatus with a separate and distinct system which I will call herein the control apparatus. The two separate systems are connected, preferably electrically, as will herein-after be more fully described, so that the attainment of an objective in the game will have a definite effect upon the control apparatus, which control apparatus in turn insures to the player the appropriate number of free games to which his completed objective entitles him.

One of the objects of the present invention is to provide an improved game apparatus.

A further object of the invention is to provide an improved free game control system.

A further object of the invention is to provide an improved coin chute which may be rendered inoperative with respect to withholding a coin or token, by suitable mechanism.

A further object of the invention is to provide an improved free game control in which balls are employed to operate as an essential part in effecting a free game, and to indicate the number of free games available and also to keep count of the free games as they are used up by the player.

Other objects, advantages and capabilities of the invention will appear from the following description of a preferred embodiment thereof, taken in conjunction with the accompanying drawings, in which:

Figure 1 is a plan view of a game embodying my invention;

Fig. 2 is a longitudinal sectional view, on a somewhat larger scale, taken on the line 2—2 of Fig. 1;

Fig. 3 is a fragmentary longitudinal sectional view, taken on the line 3—3 of Fig. 1; that is, on a plane passing through the control system;

Fig. 4 is a sectional plan detail, taken on the line 4—4 of Fig. 3;

Fig. 5 is a sectional detail, taken on the line 5—5 of Fig. 3;

Fig. 6 is a fragmentary sectional view, taken on the same line as Fig. 3, but on a somewhat larger scale and showing the control balls in a different position;

Fig. 7 is a sectional plan detail, taken on the line 7—7 of Fig. 2;

Fig. 8 is a similar view showing the manner in which a control ball serves to release the game apparatus for a free game;

Fig. 9 is a simplified view, similar to Fig. 7 but omitting a considerable amount of the mechanism shown in that figure for ease of description;

Fig. 10 is a fragmentary sectional view through the coin chute, taken on the line 10—10 of Fig. 11;

Fig. 11 is a vertical sectional fragmentary view, taken on the line 11—11 of Fig. 10;

Fig. 12 is a fragmentary inverted view showing the underside of the coin chute shown in Fig. 10;

Fig. 13 is a perspective diagrammatic view showing the relation of the various levers which cooperate with a control ball, and

Fig. 14 is an inverted plan view, taken on the line 14—14 of Fig. 2 showing the underside of the movable board, together with a wiring diagram and also a diagrammatic showing of the free game control system in relation thereto.

Referring to the drawings, the reference numeral 20 designates a board or field of a pin game, which board is provided with a plurality of openings 21 and obstacles, such as pins 22. The game is played by inserting a coin in the slide 23 which has the effect of moving forward a board 24 (see Fig. 14). The board 24 is slidably mounted on the underside of the board 20 by means of guides 25. Springs 26 normally pull the board 24 forwardly against abutments 27. The board 24 is provided with openings 28 which are out of alignment with the openings 21 of the board 20. The board 24 is provided with a bracket 29 which is adapted to be engaged by the coin slide 23 as it moves to its rearmost position, so that the board 24 is moved rearwardly against the action of the springs 26. When moved rearwardly to the full extent of the throw of the coin chute 23, the openings 28 are brought into alignment with the openings 21 and

any play balls 30 which may be located in these openings drop through to an inclined board 31, which delivers the play balls to a transverse chute 32. This transverse chute delivers the 5 balls seriatim to a suitable elevating device 33 which may be actuated periodically by the operator by means of a handle 34.

The ball elevator 33 elevates the play ball into the chute 35 at the right-hand side of the board 10 20 and the play ball may be projected along the chute by means of a spring impeller 36. The play ball struck by this impeller passes up the inclined chute 35 through a gate 37 and onto the main surface of the board 20.

15 If skillfully directed, the play ball may be caused to enter one of the openings 21. If the ball is not played into one of the openings 21 it rolls downwardly towards the front end of the apparatus and comes into contact with an automatic kicking mechanism 38 of known type. The kicking mechanism 38 comprises an electromagnet 39 and a pair of contacts diagrammatically shown in Fig. 14 at 40. One of the contacts 40 is carried by an arm 41 which is of magnetic material. The play ball which rolls down to the lower apex of the board 20 closes the contacts 40 with the result that the electromagnet 39 is energized and the arm 41 is attracted thereby. Thus, the play ball is kicked up the inclined board 20. This 25 kicking operation is continued until the ball is located in one of the openings 21.

The object of the particular game illustrated is to place balls in all of a particular group of holes 21. These groups are indicated by numerals 42 35 and arrows 43. Thus, if the player succeeds in placing four balls in the four uppermost holes 21 he becomes entitled to two free games. If he places four balls in the four lowermost holes 21 he becomes entitled to two free games. If he 40 places four balls in any of the groups illustrated on Fig. 1, he becomes entitled to two, four, six, eight or twelve free games, as indicated by the particular number 42 appertaining to the particular group.

45 The board 24 is provided with small openings 44 which are normally in alignment with the openings 21 of the board 20. That is, the openings 44 are located rearwardly somewhat with respect to the corresponding openings 28. 50 Through each opening 44 projects the upturned end 45 of resilient strips of metal 46 secured to the underside of the board 24. The location of these strips 46 for the particular groups shown in Fig. 1, is shown in Fig. 14. To complete the 55 understanding of this arrangement, we will consider the uppermost group shown in Fig. 1 and which corresponds to two free games. This group comprises five strips of metal. The strip on the left, as shown in Fig. 14, is connected to a wire 60 102. This strip terminates slightly below the second strip of the series, which is the one having the upturned end 45 projecting into the opening 44. It will readily be understood that when a played ball 30 rests upon this upturned end, 65 these two strips will be brought into contact. The second strip also has an upturned end 45 which projects upwardly through another opening 44 of the group in question. The third strip underlies this upturned end and also underlies the upturned end of the fourth strip which, like the second strip, has two upturned ends located in 70 openings 44. The fifth strip of this group underlies one end of the fourth strip and is connected to a common return wire 100. From this brief 75 description it will be seen with reference to Fig. 14

that when four balls are located in the four uppermost openings 21, a circuit will be completed between the lines 100 and 102.

From a consideration of Figs. 1 and 14, it will be seen that the completion of any group having a value of two free games will make connection between the two lines 100 and 102. The completion of a group having a value of four games will result in the completion of a circuit between the line 100 and the line 104. The completion of the group having a value of six games will result in the completion of a circuit between the lines 100 and 106. The completion of the group having a value of eight games will result in the completion of a circuit between the lines 100 and 108. The completion of the group having a value of twelve free games results in the completion of a circuit between the lines 100 and 112. The lines 102, 104, 106, 108 and 112 are connected respectively to one of the leaves of switches S2, S4, S6, 20 S8 and S12. These switches are located so as to be closed by balls in a magazine 47 of the free game control unit. Each of these switches comprises a pair of leaves and one of the leaves of each switch is connected to a line 48.

25 It may here be noted that the result of the attainment of an objective is the closing of a connection between the line 100 and one of the lines 102, 104, 106 and 112. The broader aspects of the invention are not concerned with the particular objective attained, since many objectives can be arranged which will have the effect of closing these circuits or any greater or lesser number of similar circuits. It is to be further noted that these circuits are normally closed by the control 30 balls 49 in the magazine 47 and that they become opened when these control balls no longer rest upon them.

35 Before proceeding to the description of the free game control system, certain other features 40 of the game will be disposed of.

45 Power for the operation of the device is derived from a battery 50. One conductor 51 extends from the battery to the winding of the magnet 39, which is connected through the contacts 40 to a return wire 52. The conductor 51 is connected to a tilting switch 53 and through contacts 54 carried thereby to the wire 100. The wire 100, in addition to the connections already referred to, is connected to the winding of an electromagnet 55. The other end of the winding is connected by conductor 56 to a ring 57. Within this ring is located a pendulum 58 which is electrically connected to the conductor 52. When the operator tilts the machine the pendulum 58 makes contact with the ring 57 and completes the circuit, including the battery 50 and the electromagnet 55. When the electromagnet 55 is energized it attracts the latch 59 and the tilting switch 53 is pulled by the spring 60 into a position which separates the contacts 54 and renders the machine inoperative until it is reset by the insertion of a coin or by the utilization of one of the free games which may be available to the player. When the coin slide 23 is actuated in 60 either of these events, a hook 61 engages a portion of the switch 53 so as to reset the latch 59, leaving the points 54 in contact to energize line 100. It will be understood that when the switch 65 53 opens, the whole machine is deenergized with the single exception of the electromagnet 39 of the kicker 38. The kicker, therefore, continues to operate as long as any ball makes contact with it; that is, until all the balls on the board 20 are 70 located within one of the openings 21.

When the plate 75 clears the discharging end of the magazine 47, the balls to the right of the wheel 89 move forward one step. The rearmost ball moving into the position above the plate 74 moves the arm 65 downwardly again. The balls shown immediately to the right of the lowermost tooth of the wheel 89 in Fig. 3 moves one step to the right and, consequently, the switch S2 is closed again. The star wheel 89 moves slightly in the counter-clockwise direction, this movement being permitted by the relation of the loop 86 to the teeth of the wheel 89. As a result of this limited movement all the balls 49 to the left of the wheel 89 in Fig. 3 move somewhat to the right, but all these balls are prevented from rolling down the magazine by the wheel 89. This relation is shown in Fig. 6. It may here be noted that one result of this limited movement of the balls to the forward side of the star wheel 89 is that the lever 92 is free to move from the position shown in Fig. 7 into the position shown in Fig. 9. This lever and the effect of this movement will be more fully described hereinafter. The circuit being complete through the switch S2 and between the contacts 63 and 64, the solenoid 62 is again energized to discharge a control ball into the chute 66. Upon return of the solenoid 62 the balls to the right of the star wheel 89, as viewed in Fig. 3, move up one and the switch S2 is now free to open so that further discharge of balls into the chute 66 terminates.

It will be understood that if a circuit corresponding to four free games is completed on the board 20, the circuit through the solenoid 62 is completed through the switch S4 and this switch will not open until four control balls are discharged into the chute 66. Similarly, if one of the groups corresponding to six free games is completed on the board 20, the circuit to the solenoid 62 is completed through switch S6 and this switch opens when six balls have been discharged into the chute 66. Similarly, when the group on the board 20 corresponding to eight free games is completed, the circuit to the solenoid 62 is passed through the switch S8 and this switch opens after eight control balls have been discharged into the chute 66. Likewise, when the group on the board 20 corresponding to twelve free games has been completed, the circuit to the solenoid 62 extends through the switch S12 and this switch opens when twelve balls have been ejected into the chute 66.

The boards 20, 24 and 31 are mounted in superposed relation within a cabinet 3, enclosed on its upper side by a sheet of glass 94. The front wall 95 of the cabinet carries the coin slide 23, the ball elevating handle 34 and the handle of the impeller 36. The chutes 35 and 66 are formed by means of bar portions 96 extending from a forward member 97 which is superimposed upon the board 24. The forward member 97 is provided with a suitable recess for housing part of the kicker 36. It is also provided with an opening 98 at the forward end of the chute 66 in order to enable the control balls which move down this chute to be transferred into a position above the end of the magazine 47.

The board 24 is provided with a tongue at the position 69, as shown in Figs. 1, 3 and 14. Immediately on the inner side of the tongue at the position 69 there is a long slot 99 to enable the coin slide 23 to move freely. One corner of this slot, indicated at 120, is so located as to allow the ball to drop into the magazine. That is, with reference to Fig. 14, the control ball is moved by

means about to be described, from the position 69 to 120. The coin slide 23 is mounted adjacent one corner of the cabinet and in this corner is mounted a bracket 121 upon which are pivotally mounted the lever 92 previously referred to, the lever 122 and the lever 123. The forward end of the lever 122 is pulled to the left, as viewed from above, by means of a spring 124 (see Fig. 7). The rear end of the lever 122 is extended rearwardly and to the right so that its upturned termination 125 lies in the path of the coin slide 23. When the coin slide 23 is moved rearwardly, it engages the upturned end 125 and swings the lever 122 in counter-clockwise direction about its pivot. As the rearward movement of the coin slide 23 continues, the upturned end 125 clears the end of the coin slide 23 and rides along a side 126 of the coin slide. During the final movement of the coin slide; that is, into a position shown in Fig. 8, the upturned end 125 rides on a cam portion 127 which continues the counter-clockwise movement of the lever 122.

At its forward end the lever 122 is provided with an upturned web 128 (Figs. 3 and 13). This web is adapted to move freely in a space 129 left between the position 69 of the board 24 and the front wall of the cabinet. At its upper end the web 128 carries a rearwardly extending flange 130 which normally lies on the outer side of the chute 66, as shown in Fig. 1. When the lever 122 is swung in counter-clockwise direction as described above, the flange 130 moves across the chute 66 and delivers a control ball into the position 120 above the forward end of the magazine 47. In such an event the control ball comes into contact with a flange 131 which is normally located on the right-hand side of the chute 66, as shown in Fig. 1. The flange 131 is carried by a web 132 on the rear of the lever 123. The web 132 extends upwardly through and works in the portion 120 of the slot 99 shown in Fig. 14.

The lever 123 is held in its normal position by means of a spring 133 which is connected to the bracket 121. The levers 122 and 123 are provided respectively with projections 134 and 135 which are directed toward each other. One of these projections, for example the projection 135, has an upturned end 136 for the purpose of insuring contact with the other projection 134. Referring particularly to Fig. 7, it will be noted that the projections 134 and 135 are so located that they will not make contact when the lever 122 is moved independently of the lever 123. That is, if there is no ball in the chute 66 and the coin slide 23 is moved rearwardly to its fullest extent after the insertion of the appropriate coin, then the lever 122 alone is swung in counter-clockwise direction. The lever 123 is not swung and the projection 134 moves past the projection 135 without contacting it or its upturned end 136. If, on the other hand, the slide 23 is moved rearwardly to its fullest extent and a control ball 49 is in the forward end of the chute 66, then the lever 123 is swung in counter-clockwise direction by the ball, which is pushed by the flange 130. This movement of the lever 123 brings the two projections 134 and 135 into colliding relation and the relationship of these flanges to the pivots of the two levers 122 and 123 is such that in the last part of the movement of the levers the forward ends are caused to separate and the ball 49 is thereby freed so that it may fall into the magazine 47. This relation of the levers is shown in Fig. 8.

The lever 123 is provided with an end which 75

The conductor 52 is connected to a solenoid 62 which forms part of the free game control device. The other end of the solenoid 62 is connected to a contact 63. The wire 48 is connected 5 to a contact 64. The contacts 63 and 64 are adapted to be connected and disconnected by means of an arm 65, the operation of which will appear from the following description of the free game control system.

10 The free game control system comprises a chute 66 on the left-hand side of the board 21. This chute is closed from the rest of the board 21 by a gate 67 so that the balls of the control device and the balls with which the pin game is played 15 never come into contact or commingle. The control balls are discharged into the chute 66 by an opening 68 near the upper end thereof and they roll down to a position 69 at the forward end from which they are dispensed as the available 20 free games are played. The control ball thus used passes into the magazine 47 previously referred to. As best shown in Fig. 3, the magazine 47 slopes downwardly from the front of the machine and terminates at a position below the 25 opening 68. The magazine may suitably comprise a three-sided elongated box which is open on its underside. It is provided on its inner side with a pair of parallel rails 70 upon which the control balls 49 ride. Owing to the downward 30 and rearward slope of the rails 70, the balls are closely packed within the magazine and in the event that certain of the balls are removed from the right-hand end of the magazine, the remaining balls will move up to the right. The leaves 35 of the switches S2, S4, S6, S8 and S12 are located between the rails 70 and the manner in which these switches are closed by the balls 49 is best shown in Fig. 3. It will be noted that the rails 70 are stepped adjacent the points of contact of 40 the balls 49 with the upper leaves of these switches so that a ball moving down one of the steps firmly closes the switch next below the step.

At the rear end of the magazine 47 is located an upwardly directed conduit 71 which terminates 45 in the opening 68. At the lower end of the conduit 71 is located the solenoid 62 previously referred to. The armature 72 of the solenoid carries at its upper end a rod 73 of non-magnetic material which carries a plate 74. From the forward side of the plate depends a plate 75. When the solenoid 62 is energized, the armature 72 moves upwardly and the rod 73, together with the plate 74, is moved up to carry a control ball 49 upwardly into the conduit 71 past a dog 76. 50 When the plate 74 moves upwardly the plate 75 prevents the entrance of a further ball from the magazine 47 into the conduit 71. The dog 76 is substantially of rectangular construction, being pivoted at the angle so that a short arm extends 55 into the conduit 71. The long arm extends upwardly and is normally held in that position by a spring 77.

With reference to Fig. 3 it will be seen that the dog 76 may swing in the counter-clockwise 60 direction to permit a control ball 49 to move past it. After the control ball is moved past it, the dog 76 resumes the position shown in Fig. 3 and the downward movement of the ball is prevented. The conduit 71 above the dog 76 is normally 65 filled with control balls 49. When energization of the solenoid 62 results in the upward movement of a control ball 49 past the dog 76, a corresponding control ball 49 is discharged at the opening 68 to give the player a free game.

75 The contacts 63 and 64 and the arm 65 are

carried by a piece of insulation 78 which is carried by the lower end of the conduit 71. The rod 73 is provided with a slot 79 and the arm 65 extends through an opening 80 in the wall of the conduit 71 into the slot 79. The contacts 63 and 64 are so located that the presence of a control ball 49 at the lower end of the conduit 71 serves to hold the arm 65 downwardly, thus completing a circuit between the contacts 63 and 64. When, however, the arm 65 moves upwardly, 10 the shoulder at the lower end of the slot 79 engages the arm 65 and breaks the circuit between the contacts 63 and 64. The result is that the solenoid is deenergized and the armature 72, together with the rod 73, plate 74 and plate 15 75 return to their initial position. Unless the circuit is interrupted by the opening of one of the switches S², S⁴, S⁶, S⁸ or S¹², the solenoid 62 continues to be energized and deenergized so that control balls 49 are delivered one after another 20 into the chute 66.

The rod 72 and the parts mounted thereon are prevented from turning by means of a rod 81 which has a major portion parallel to the rod 72, which major portion is slidably received by 25 an opening in plate 82 carried at the lower end of the solenoid 62. When the armature 72 moves upwardly, the rod 81 swings a rod 83 in the counter-clockwise direction, as viewed in Fig. 3. The rod 83 is pivotally mounted on top of the 30 magazine at 84 and is rigidly connected to a forwardly extending latch 85. This latch is adapted to engage a loop 86. The loop 86 carries a forwardly extending integral rod 87 which terminates in an upturned end 88. The loop 86 and 35 the rod 87 are slidably mounted on the upper side of the magazine 47 and are normally pulled forwardly by means of a spring 89. When the coin slide 23 is moved rearwardly at the beginning of a game, it engages the upturned end 88 40 and moves the loop 86 and rod 87 rearwardly into a position in which they are held by the latch 85. The forward portion of the loop 86 is adapted to move into and out of the path of a star wheel 89 rotatably mounted on the upper side 45 of the magazine 47 and having teeth 90 which project through a slot 91 into the interior of the magazine so as to contact the control balls 49.

At the beginning of the game the control balls 49 are located as shown in Fig. 3; that is, the 50 magazine 47 is full of balls and the first ball at the forward end of the magazine has the position shown in full lines in Fig. 7. The loop 86 is in its rearward or latched position, because the fact that there are no balls in the chute 66 means 55 that the last free game has been expended and the forward movement of the coin slide 23 to play that game has latched the loop 86 in its rearward position. The star wheel 89 is arranged so that one of its teeth 90 is directed downwardly, as 60 shown in Fig. 3. The game is started by placing a coin in the coin slide 23 and moving it forwardly so as to clear the board 21 and render the play 65 balls 30 available. If the player completes the group corresponding to two free games, for example, the circuit through the solenoid 62 is completed and the armature 72 is moved upwardly. This upward movement effects the discharge of one ball into the chute 66. It also effects the unlatching of the loop 86 so that it moves forwardly into a position adjacent and rearward of one of the teeth 90. The upward movement of the arm 65 causes the deenergization of the solenoid 62 so that the armature 72 moves downwardly again.

extends to the right behind its pivot. This end of the lever 123 is pivotally connected to a slidable member 137 which cooperates with the coin slide 23 in a manner which will hereinafter be described in greater detail. The lever 123 carries a depending pin 138 which is adapted to engage the lever 92 previously referred to. The lever 92 has at its forward end a depending flange 139 which extends into the forward end 10 of the magazine 47. When the magazine is filled with control balls, the flange 139 is in engagement with the last inserted ball; that is, the one at the forward end as shown in Fig. 8. When, however, the player makes his objective and a control ball 49 has been elevated into the tube 71, as previously described, and the wheel 89 has become locked, the balls to the right thereof have moved one space to the right as viewed in Fig. 3, then the rearward movement of the balls 20 to the left of the wheel 89 into the relation shown in Fig. 6 moves the forward ball 49 forwardly somewhat so that the lever 92 may move under the action of its spring 140 into the position shown in Fig. 9. The result of this position is 25 to render the coin slide 23 inoperative except by the use of the free ball after it has rolled down the chute 66 to the forward position 69.

For this purpose the lever 92 is provided with an upturned end 141 which is arranged to make 30 contact with an abutment 142 on the underside of the coin slide 23. It will be seen with reference to Fig. 9, that if the coin slide 23 is moved rearwardly the abutment 142 will contact the upturned end 141 of the lever and will thereby 35 become arrested even if a coin is inserted. When, however, the ball has arrived at the forward end of the chute 66, a coin is inserted in the coin slide which is then moved rearwardly, the coin slide actuates the lever 122, the control ball 49 actuates the lever 123 and the depending pin 138 on the lever 123 engages the lever 92 and rotates it out of its position shown in Fig. 9 40 into its position shown in Fig. 8. This change of position of the lever 92 enables the control ball 49 to drop into the forward end of the magazine 47. The forward edge of the abutment 142 is suitably curved so that this abutment may move past the upturned end 141 when the coin slide 23 is being pulled back.

50 The coin slide 23 may be of conventional design, for the most part, and may be provided with a complete stroke pawl 143 and other devices for rendering the chute inoperative except by the appropriate coin or token. The coin 55 or token is placed in an opening 144 in the coin slide and it is moved upwardly into a race 145 where the coin is arrested by a spring 146 for inspection through a suitable opening 147.

The upward movement of the coin out of the 60 slide 23 is effected by means of a pawl 148 which is pivotally mounted below the coin slide 23. The pawl 148 is provided with a spring 149 which tends to move it into its dotted-line position shown in Fig. 11. In that position the 65 pawl 148 elevates the coin out of the coin slide 23 over the block 150 in which the race 145 is formed. The pawl 148 is provided with a pin 151 which is adapted to be engaged by a cam 152 projecting downwardly from the slidable member 137. The link or slidable member 137 is provided with a slot 153 through which extends a pin 154 carried by a rigid part of the frame in which the coin slide 23 operates. In its 70 normal position the pawl 148 moves a coin out 75 of the coin slide into the race 145. When, how-

ever, a ball 49 is present at the forward end of the chute 66, the lever 123 is moved in the manner above described, the link 137 is moved rearwardly and the cam 152 depresses the pawl 148 into the full line position shown in Fig. 11. Consequently when, in the continued rearward movement of the slide 23, the coin reaches a position above the pawl 148, this pawl is inoperative and the coin moves rearwardly into the position shown in Fig. 11. When the coin slide 10 is drawn forwardly again, the coin is in the opening 144 and may be picked up by the player.

The operation of the device will be readily apparent from the description thereof contained above, in connection with the various elements 15 of the machine. For convenience of the reader, a brief summary of the operation is given for the purpose of correlating the functions of the several parts.

In the initial operation of the machine there 20 are no control balls in the chute 66. The play balls occupy positions in the openings 21 and the magazine 47 is full of control balls and the conduit 71 contains one ball above the plate 74 and five balls above the latch 76. Consequently, all the switches S2, S4, S6, S8 and S12 are closed. The wheel 89 is latched as shown in Fig. 3, since the last unsuccessful play entailed the forward movement of the rod 87 and frame 86. The lever 92 is held by the foremost 30 ball 49 in the position shown in Fig. 8. Consequently, when the player inserts a coin or token in the opening 144 and moves the coin slide 23 rearwardly, this movement of the coin slide is not prevented by the rearward upturned 35 end 141 of the lever 92. The rearward movement of the coin slide 23 swings the lever 122, but this movement has no effect owing to the absence of all the control balls from the chute 66. Owing to the fact that the lever 123 is not 40 moved by the lever 122, the pawl 148 is in the dotted-line position shown in Fig. 11 and the coin is elevated into the race 145. The forward movement of the coin slide 23 causes it to engage the bracket 29 with the result that the board 24 is moved rearwardly, bringing the openings 45 23 into alignment with the openings 21.

The play balls 30 drop through the aligned openings and roll down over the board 31 into the chute 32 where they are available to the 50 player. If the player fails to locate balls in all the holes 21 of one group, then the game is terminated and a coin must be inserted to start a new game. If, however, the player attains an objective; that is, if he locates balls in all the 55 holes 21 of one group, then the operation of the solenoid 62 starts and continues until the appropriate number of balls corresponding to that objective have been delivered into the chute 66. As has been previously described, the first 60 operation of the solenoid 62 unlatches the frame 86 so that it may move into a position to block the wheel 89. The solenoid continues to operate repeatedly until the ball immediately on the right of the wheel 89 clears the particular switch S2, 65 S4, S6, S8, S12 of the energizing circuit.

On the return of the armature 72 after elevating the first ball, the balls to the right of the star wheel 89 move forward one step and the balls to the left of the star wheel 89 move forward part of a step and at least sufficient to enable the lever 92 to move from the position shown in Fig. 7 to its position shown in Fig. 9. As has heretofore been explained, the result of this change of position of the lever 92 is to 75

bring the abutment 141 into alignment with the abutment 142. When this occurs the player must wait until the first control ball arrives at the position 69 before he can move the coin slide 23 rearwardly. To move the coin slide 23 at all, he must have inserted an appropriate coin. The abutment 141 is rendered inoperative to arrest the rearward movement of the coin slide when the ball is present at the position 69. When this occurs, as has been previously described, the lever 122 actuates the lever 123 by means of said ball and the lever 123 swings the lever 92 so that the upturned end 141 is moved out of the path of the abutment 142.

- 15 15 The same movement of the lever 123 effects the movement of the cam 152 and the pawl 148 into the position shown in full lines in Fig. 11, with the result that the coin can be regained by the player after he pulls the slide 23 back.
- 20 20 Although the invention has been disclosed in connection with the specific details of a preferred embodiment thereof, it must be understood that such details are not intended to be limitative of the invention except in so far as set forth in 25 the accompanying claims.

Having thus described my invention, what I claim as new and desire to secure by Letters Patent of the United States is:

- 30 1. The combination of a game apparatus in which a plurality of playing balls is adapted to be projected over a playing surface, a coin controlled mechanism for rendering the apparatus operable, means normally positioned to effect removal of a coin from said coin controlled mechanism upon actuation thereof, means connected to the coin removal means adapted to render it ineffective, a control ball adapted to be released at a predetermined time in the playing of the game, means for releasing the control ball, and 35 means controlled by said coin controlled mechanism upon a subsequent operation thereof adapted to move said control ball into operative relation with said means for moving the coin removing means to its inoperative position.
- 40 2. A device as in claim 1, including a magazine in said apparatus, a plurality of control balls in the magazine, a runway connected to said magazine, means determining the number of balls which may be delivered from the magazine to the runway, said balls when in said runway being adapted to cooperate with the means for moving the coin-removing means to its inoperative position.
- 45 3. A device as in claim 1, including a magazine in said apparatus, a plurality of control balls in the magazine, a runway connected to said magazine, means determining the number of balls which may be delivered from the magazine to the runway, said balls when in said runway being adapted to cooperate with the means for moving the coin-removing means to its inoperative position, said determining means comprising a plurality of electric circuits adapted to be closed by means engaged by playing balls in predetermined positions on said surface, and a control mechanism operated on the closing of any one of said circuits for releasing a number of control balls as predetermined by the circuit closed.

4. The combination of a game apparatus including a playing surface having recesses, playing balls adapted to be projected over said surface and to be held in said recesses, a coin controlled mechanism for rendering said apparatus operable to project said playing balls over said surface, means normally positioned to effect removal of a coin from said coin controlled mechanism upon actuation thereof, means connected to said coin removal means for moving it into an inoperative position, a plurality of control balls adapted to be released at a predetermined stage in the playing of the game, means actuated by locating playing balls in predetermined recesses of said playing surface for releasing one or more of said control balls and means controlled by said coin controlled mechanism upon a subsequent operation thereof to move a released control ball into operative relation with said means for moving the coin removing device to its inoperative position.

5. In a free game apparatus a magazine adapted to control a plurality of control balls, a series of switches adapted to be closed by said balls, locking means adapted to separate said balls within the magazine, means for elevating the balls from said magazine seriatim, said elevating means including electromagnetic means in circuit with said switches, and means for unlocking said locking means.

6. In a free game apparatus a coin slide, means normally operative to remove the coin from the slide, control balls, a lever movable with said slide adapted to engage and move a control ball, and a lever adapted to be engaged and moved by said control ball, said last lever being connected to the means for removing the coin so as to render it, when actuated by a control ball, inoperative.

7. In a free game apparatus a playing surface over which play balls are adapted to be played, switches on the playing surface adapted to be closed by said balls, a free game control device comprising switches in circuit with certain of the switches on the playing surface, a solenoid adapted to be energized by simultaneous closing of certain switches on the playing surface and certain switches on the control device, a magazine in said control device, control balls therein normally closing said switches of the control device, an armature for said solenoid adapted to elevate control balls therefrom seriatim, contacts adapted to be opened by the upward movement of said armature to break the circuit through said solenoid, whereby intermittent elevation of control balls continues until the circuit is broken by one of said switches in the control device, means for rendering the play balls available to the player, including means cooperating seriatim with said control balls after their elevation and for returning said control balls seriatim to the magazine, a spur wheel adapted to separate the control balls in the magazine into two groups, and means for locking and unlocking said wheel, the switches of the magazine being located in a series near one end of the magazine and said magazine sloping downwardly towards that end.

WILLIAM H. BELLAH.
